DESIGN FOR A PITCHER OR SIMILAR ARTICLE

Walter Oehrle, Pelham, N. Y., assignor to The Borden Company, New York, N. Y., a corporation of New Jersey

Application January 7, 1943, Serial No. 109,218

Term of patent 14 years

To all whom it may concern:

Be it known that I, Walter Oehrle, a citizen of the United States, residing at Pelham, in the county of Westchester and State of New York, have invented a new, original, and ornamental Design for Pitchers or Similar Articles, of which the following is a specification, reference being made to the accompanying drawing, forming a part thereof.

In the drawing:

Figure 1 is a side elevational view of a pitcher or similar article, showing my new design;

I claim:

The ornamental design for a pitcher or similar article, as shown.
